E. G. TOY

VALVE LOCK

Filed April 10, 1925

UNITED STATES PATENT OFFICE.

EUGENE G. TOY, OF NUTLEY, NEW JERSEY, ASSIGNOR TO THE BARBOUR FLAX SPINNING COMPANY, OF PATERSON, NEW JERSEY, A CORPORATION OF NEW JERSEY.

VALVE LOCK.

Application filed April 10, 1925. Serial No. 22,007.

To all whom it may concern:

Be it known that I, EUGENE G. Toy, citizen of the United States, residing at Nutley, in the county of Essex and State of New Jersey, have invented certain new and useful Improvements in Valve Locks, of which the following is a specification.

This invention relates to valve structures of the type in which the valve proper is closed or opened by rotating it by hand one way or the other by means of a spindle forming an extension of the valve and having a handle, and it consists in a novel construction of valves of this type in which the handle part of the structure including the handle and valve proper may be rendered inoperative to screw in or screw out the valve to seat or unseat the same except by application of a suitable key, whereby only a person having the key can effect opening or closing of the valve when the handle has been left in the inoperative state. The invention is designed to serve in the many instances where it is necessary to protect a valve from manipulation by unauthorized persons. Given a valve casing, a valve member screwed therein and including a spindle having a rigid prolongation, the invention consists in providing the prolongation with a handle revolvably held thereon and key-operated means in the prolongation to lock the handle to the latter, whereby according as the locking is not or is effected the handle will be inoperative or operative for turning the valve. The invention consists also in other features involving protecting the lock against being tampered with and protecting the handle and lock mechanism from being removed from the valve spindle and from possible injury.

In the drawing,

Fig. 1 is a side elevation, partly in section, of the improved valve mechanism;

Fig. 2 is a view in section of said mechanism on a larger scale;

Figs. 3 and 4 are sections on line 3-3 and 4-4, Fig. 2;

Fig. 5 shows in side elevation, partly in section, and in end elevation the lock barrel; and

Fig. 6 is a perspective view of a certain forked plug.

A globe valve such as is ordinarily used

for steam radiators is shown. *a* is its casing and *b* the valve spindle the valve of which (not shown) is moved to and from seating position in the valve casing by rotating the spindle, which is threaded in the usual way in the upstanding extension *a'* of the casing. On the extension is a gland *c* which I make of special form for a purpose to be stated and which coacts in the usual way with the gasket *a''* which surmounts the valve packing (not shown) contained within said extension.

The spindle *b* is by my invention cut off and formed at the top with a tenon *b'*. *d* is the lock barrel. It has an upper end wall *d'* apertured to receive a key, but its lower end is open and also bifurcated, as at *d''*, Fig. 5. It contains a plug *e* in its lower end, correspondingly bifurcated, as at *e'*, and said plug is held therein by a pin *f* penetrating it and the barrel so that the slots in their bifurcations register and form a mortise. When the valve spindle and barrel, with its contained plug, are assembled the mortise receives the tenon of the spindle, and to hold the parts together there are provided a collar *g* embracing them and a screw *h* which is tapped through the several parts at the mortise and tenon connections then formed. The barrel has a pair of opposed holes *d''* (Fig. 5) and another pair of opposed holes *d''* (Fig. 3) the purpose of which will appear. The plug *e* has an upstanding lateral stop *e''*, the purpose of which will also appear.

i is the valve handle, including a circular handle proper *i'* and a depending cylindrical shank *i''* whose bore is adapted to receive the barrel *d*, which affords a bearing therefor. Its lower end is enlarged, as at *i''*, and has an internal annular groove *i''* and pairs of opposed holes *i''* communicating with said groove.

j is the bolt. It exceeds in length the diameter of the bore of the handle *i* so that when the parts are assembled (by fitting the handle to the barrel so that their holes *d''* and *i''* are alined and introducing the bolt endwise thereto) the bolt in any position to which it is then shifted confines the handle against detachment from the barrel. When the bolt is shifted lengthwise into one of the holes *i''* the handle is locked against rotation relatively to the

barrel; when it is shifted to clear both holes i^s the handle may swivel on the barrel.

k is the bolt actuating cam which is a 5 cylindrical block revoluble in the barrel above the bolt and having an eccentric tang k' engaged in a cross-slot j' of the bolt. It is retained in the barrel by having an annular groove k^2 thereof engaged by 10 a projection formed internally in the barrel (at d^5 , Fig. 5) by a prick-punch. Its upper end has a suitable notch k^3 to receive the key A. For holding the bolt at either 15 limit of its movement the cam k has a transverse bore k^4 which contains a spring k^5 pressing apart two balls k^6 adapted to enter holes d^4 of the barrel and thus releasably hold the cam against turning.

The stop e^a of the plug e , by receiving contact of the tang k' of cam k , limits the movement of the cam to a half-turn, the bolt being shortened at one side of its slot j' so that when the cam is shifted a half-turn in one direction the bolt will clear the handle, leaving it free to swivel, and when it is shifted a half-turn in the other direction the bolt will enter a hole i^s of the handle and lock it.

The locking mechanism is protected against tampering, as through holes i^s by 30 an upstanding guard c' formed on gland c .

At l is a plug tapped into guard c' in the zone of screw h . This is flush with the outer surface of the guard and may only be turned by employing a special tool, as a spanner 35 wrench.

The handle with the barrel and its contained parts is assembled with the valve spindle b by fitting the mortise to the tenon with the collar on the protruding end of the 40 barrel and then applying the screw h , plug l being first removed for the purpose.

The lock mechanism is made inaccessible through the handle from the top, except by the key, by a key-guide plug m permanently 45 secured in place, as by a split-ring n engaged in mating grooves in the plug and handle (see Fig. 2).

The gland-extension c' or guard performs three functions: It prevents tampering in 50 any position of the valve (which appears fully screwed in in Fig. 1 and screwed out in Fig. 2) with the locking device and also with the joint between the spindle and the prolongation of the latter formed by the 55 lock barrel and it also reinforces the joined spindle and prolongation against distortion by a blow or other strain, it being noted that it snugly fits the lower portion of the handle shank for an appreciable extent thereof even when the valve is fully screwed out, or open.

The collar g serves to reinforce the joint between the spindle and prolongation by embracing the overlapping portions of these two parts.

Having thus fully described my invention what I claim and desire to secure by Letters Patent is:

1. In combination, a valve casing, a valve member screwed therein and including a 70 spindle protruding from the valve casing and having a rigid prolongation, a handle held revolubly on the prolongation, and key-operated means in the prolongation to lock the handle against rotating relatively 75 thereto.

2. In combination, a valve casing, a valve member screwed therein and including a spindle protruding from the valve casing, a lock barrel alined with and rigidly jointed 80 to the spindle, a handle held revolubly on the lock barrel, key-operated means in said barrel to lock the handle against rotating relatively thereto, and a guard projecting from the casing and surrounding the joint 85 between the spindle and barrel.

3. In combination, a valve casing having a packing-receiving extension, a valve member screwed in the casing and including a 90 spindle protruding through the extension and having a prolongation, a handle having a cylindrical shank revolubly held on the prolongation and formed with a locking hole, key-operated locking mechanism in the 95 prolongation including a locking device 100 movable into and out of said hole, and a gland screwed on the extension and having a guard extending therefrom and surrounding the portion of the handle shank having said hole in any position of the spindle.

4. In combination, a valve casing having a packing-receiving extension, a valve member screwed in the casing and including a spindle protruding through the extension, a lock barrel jointed to and forming a 105 prolongation of the spindle, a handle having a cylindrical shank revolubly held on the prolongation and formed with a locking hole, key-operated locking mechanism in the barrel including a locking device movable into 110 and out of the hole, and a gland screwed on the extension and having a guard extending therefrom and surrounding the joint between the spindle and barrel in any position of the spindle.

5. In combination, a valve casing having a packing-receiving extension, a valve member screwed in the casing and including a spindle protruding through the extension and having a prolongation, a handle having a cylindrical shank revolubly held on the prolongation and formed with a locking hole, key-operated locking mechanism in the prolongation including a locking device 120 movable into and out of the hole, and a gland screwed on the extension and having a projecting portion formed around and 125 snugly fitting the handle shank.

In testimony whereof I affix my signature.
EUGENE G. TOY.
